UNITED STATES PATENT OFFICE.

JOHN J. DIXON, OF BOSTON, MASSACHUSETTS.

RAILWAY-SWITCH.

SPECIFICATION forming part of Letters Patent No. 600,859, dated March 22, 1898.

Application filed November 6, 1896. Serial No. 611,238. (No model.)

To all whom it may concern:

Be it known that I, JOHN J. DIXON, a citizen of the United States, residing at Boston, in the county of Suffolk and State of Massachusetts, have invented certain new and useful Improvements in Railway-Switches; and I do hereby declare the following to be a full, clear, and exact description of the invention, such as will enable others skilled in the art to 10 which it appertains to make and use the same.

This invention has reference to a novel construction in a switch for railways, and more particularly to devices for operating switches of electric and street railways.

15 The invention consists in the features of construction hereinafter fully described and claimed.

In the accompanying drawings, forming a part of this specification, Figure 1 is a top 20 plan of a switch provided with operating devices constructed in accordance with this invention. Fig. 2 is a side elevation, partially in section, of said switch and operating device and a car provided with a projection for operating this device. Fig. 3 is an end elevation of the switch-operating lever and accompanying parts. Fig. 4 is a side elevation of the same.

Referring now to said drawings, 1 indicates 25 the rails of the track, 2 the switch-rails, and 3 the tongue, which forms a section of and is pivoted to one of the rails of the main track 1. The said tongue 3 is mounted upon the upper end of the rotatable pin 4, mounted in 35 suitable bearings below the rail and preferably squared at its upper and lower ends and cylindrical in its middle portion, whereby it may be firmly attached to the tongue and to a rod 5 below the same. Situated upon the 40 main track at a little distance from the tongue and conveniently within a well below said track is a vibratory lever 6. This said lever 6 consists of a cross-bar having upright end portions 8 and a depending stem 9. These 45 upright end portions or arms 8 are provided at their upper ends with heads 10, that are pivoted thereto in the manner shown and extend upwardly through slots 11 in the bed of the track. These slots 11 are situated at the 50 lower end of the downwardly-inclined grooves 12 on opposite sides thereof. The lever 6 is

so arranged that when one of these slots 10 stands above the lower face of the groove 12 the other is situated below the same, this position being secured by the rocking of this 55 lever. The lower end of the stem 9 is provided with a projection 13, to which is pivoted a rod 14, that extends upwardly and is pivoted at its other end to the rod 5, connected with the pin 4. It will be seen from 60 the foregoing description that when the vibratory lever 6 is rocked it will, through the intermediacy of the rods 14 and 5 and pin 4, throw the switch-tongue 3 to one side or other to open or close the switch. To lock the said 65 vibratory lever, and consequently the switch-tongue, in either of its positions and against accidental movement, a spring-bolt 15 is mounted upon the top plate 16 and has a double-beveled end adapted to engage the upper 70 or lower edge of the cross-piece of the vibratory lever. This spring-bolt will be drawn back by the movement of the lever, so that while it holds it against accidental displacement it allows it to move when force is applied thereto. This switch-operating mechanism is manipulated by a projection carried by a car, and in Fig. 2 is shown an upright 75 movable stem 17, provided at its lower end with a shoe 18 and at its upper end with a foot-piece 19. A spring 20 serves to lift the said stem and shoe, while it is depressed by means of a foot-piece. An operating projection of this kind is situated at each side of the car, so that the switch can be either opened or 80 closed by the car, it being noted that the operating-heads of the switch device are either elevated or depressed as the switch is opened or closed.

It is preferable to make the outer end portion of the groove inclined upwardly, as shown in said drawings, so that the shoe first rides upwardly and then downwardly to operate the switch.

Having thus described my invention, what 95 I claim as new, and desire to secure by Letters Patent, is—

1. The combination with the tongue of the switch of an upright pivot to which said tongue is secured, a rod secured to said pivot and pinned to rod 14, and rod 14 pinned to the projection 13 of the vibratory lever 6 so that

the said vibratory lever with depending stem 9, will throw the tongue either way at will by the rocking of the vibratory lever.

2. A vibratory lever having heads situated 5 within the path of a projection on the car, a switch-tongue connected with and operated by said lever, and a spring-bolt situated in the path of said lever.

3. The combination with the rails of a track 10 and slots situated adjacent thereto, of a vibratory lever having pivoted heads situated within said slots, a cross-piece, a depending

stem, and a projection upon said stem, a rod pivoted to said projection and to another rod, said last-mentioned rod being connected with 15 an upright pivot to which a switch-tongue is rigidly connected.

In testimony whereof I have signed this specification in the presence of two subscribing witnesses.

JOHN J. DIXON.
